UNITED STATES PATENT OFFICE.

OLAF SELMER, OF LILLEHAMMER, NORWAY, ASSIGNEE TO CHRISTEN SEEBERG, OF CHRISTIANIA, NORWAY.

SKEE-HARNESS.

1,113,496.

Specification of Letters Patent. Patented Oct. 13, 1914.

Application filed December 20, 1913. Serial No. 807,829.

To all whom it may concern:

Be it known that I, OLAF SELMER, a subject of the King of Norway, residing at Lillehammer, Norway, have invented certain 5 new and useful Improvements in Skee-Harness; and I do hereby declare the following to be a full, clear, and exact description of the invention, such as will enable others skilled in the art to which it appertains to 10 make and use the same, reference being had to the accompanying drawings, and to letters or figures of reference marked thereon, which form a part of this specification.

My invention relates to a new skee harness 15 comprising means acting upon the projecting rim of a boot sole and clamping the latter to the skee body, thereby maintaining the boot in a fixed position upon said skee body.

20 In the following I shall proceed to describe my invention clearly with reference to the annexed drawings illustrating some embodiments of my invention.

On the drawings: Figure 1 is a sectional 25 front elevation of an embodiment of my invention. Fig. 2 is a side elevation of another embodiment of my invention. Fig. 3 is a front elevation of the harness shown on Fig. 2 the skee body being shown in section 30 on a line some distance in front of the harness. Fig. 4 is a sectional elevation of a further modification on the harness.

Corresponding parts are indicated by the same letters on all the drawings.

35 A indicates the skee and B the boot sole.

On the form of harness shown on Fig. 1 the clamping means are formed by bell crank levers F, C pivoted at D on the lateral lugs E. The long arms C of said bell crank

40 levers are standing up, while the shorter arms F, which are formed as thumbs or bosses are resting upon the projecting rim of the sole, when the latter is placed as shown between the lateral lugs E. The upper 45 ends of the long arms C are connected by means of a strap G or the like, by means of which they may be drawn toward each other. This movement of the arms C causes the short arms F to be pressed against the 50 rim of the sole thereby clamping the latter to the skee body A and maintaining the boot in a fixed position. To prevent any slight

movement of the sole B upon the skee body A a base plate is provided between the lateral lugs I having short spikes, as will be 55 clearly seen on the drawing, said points entering into the bottom of the sole. The said base plate as shown on Fig. 1 may be formed by the connecting piece between the lugs E.

In the harness illustrated on Figs. 2 and 3 60 the clamping levers C, F are mounted to swing in longitudinal planes instead of a transverse plane as shown on Fig. 1. The long arms C project in a forward and upward direction forming a bail in front of 65 the boot. The said bail by means of the strap G or a similar appliance may be pulled downward thereby pressing the short arm or thumb F on the projecting rim of the sole as is clearly shown on the drawings. 70

In the harness illustrated on Fig. 4 the lateral lugs are movable and besides steady- 75 ing the boot in a lateral direction by means of lateral pressure on the sole also performs the function of clamping the projecting rim of the sole to the skee body. In the harness shown on Fig. 4 the movable lateral lugs are formed by one armed levers C pivoted to swing in a transverse plane. The said levers are provided with bosses or thumbs 80 F projecting inwardly and acting upon the upper side of the sole rim so as to press the latter upon the skee body, when the arms C are drawn toward each other by means of the strap G. At the same time the levers C 85 effect the necessary lateral steadyng of the sole. The journals D for the pivoted levers C may be formed by the laterally projecting parts of a wire loop mounted in the strap hole of the skee body. The levers C may be 90 removably hooked around the journals D.

I claim—

1. In a skee harness the combination with the skee-body of side lugs, one on each side of the skee-body, levers pivoted to said lugs 95 and comprising each a short arm adapted to act upon the projecting rim of a boot sole for clamping the same to the skee-body, and a long arm for moving the short arm against the projecting rim of the boot sole. 100

2. In a skee harness the combination with the skee-body of side lugs, one on each side of the skee-body, levers pivoted to said lugs and comprising each a short arm adapted

to act upon the projecting rim of a boot sole for clamping the same to the skee-body, and a long arm for moving the short arm against the projecting rim of the boot sole, and means for drawing the long arms toward each other and holding them in position.

5 In testimony that I claim the foregoing

as my invention, I have signed my name in presence of two subscribing witnesses.

OLAF SELMER.
